FUEL ATOMIZING NOZZLE

Filed Sept. 30, 1929

UNITED STATES PATENT OFFICE

PAUL LEO JOSLYN, OF SAN FRANCISCO, CALIFORNIA, ASSIGNOR TO JOSLYN DIESEL ENGINE COMPANY, LTD., OF SAN FRANCISCO, CALIFORNIA, A CORPORATION OF CALIFORNIA

FUEL ATOMIZING NOZZLE

Application filed September 30, 1929. Serial No. 396,360.

This invention relates to improvements in fuel atomizing nozzles and has particular reference to a device which may be employed either for atomizing fuel in an internal combustion engine or in a boiler where the fuel is under continuous combustion.

Another object is to produce a device which will produce a high degree of atomization of fuel at a low pressure irrespective of the amount of fuel used.

An additional object is to provide a nozzle which will prevent after-dripping upon the closing of the oil supply.

Another object is to produce a nozzle which will eliminate carbon forming upon the tip and thus interfering with the proper operation of the same, even when used in an engine idling for a long period.

A further object is to produce a nozzle which will operate at a considerably reduced pressure thus eliminating considerable wear especially on small orifices.

A still further object is to produce a jet wherein a wide spread of flame is effected.

Other objects and advantages will be apparent during the course of the following description.

In the accompanying drawings forming a part of this specification and in which like numerals are employed to designate like parts throughout the same,

Figure I is a cross sectional view of an inlet valve having my jet attached thereto,

Figure II is a fragmentary view in cross section of my jet as applied to a boiler burner,

Figure III is a bottom plan view of the atomizer disc, and

Figure IV is a bottom plan view of a tip disc.

In using crude oil for internal combustion engines, it has been found necessary to inject the oil into the cylinder under high pressure and that with the present type of valves in use, it is only possible to idle the engine to a limited degree and in boilers where the low grade fuel is burned the present day type of jet produces a long flame which is injurious to the boiler, has low efficiency and requires a heavy pressure while with

my nozzle a relatively low pressure is employed but a better combustion obtained thus increasing the efficiency of the boiler and due to the low pressure the life of the tips is much longer.

In the accompanying drawings wherein for the purpose of illustration is shown a preferred embodiment of my invention, the numeral 5 designates a valve casting adapted to be employed with an internal combustion engine of the Diesel type. It is obvious, however, that my nozzle may be employed in any type of engine. To this valve casting 5 is secured a head 6 in which is threadedly secured a screw 7 having a downwardly extending tip 8 which passes through a spring cap 9 against which a spring 11 contacts. A spring block 12 is engaged by the opposite end of the spring 11 and bears upon the valve rod 13. This valve rod travels in a bushing 14 which bushing is provided with oil channels 16 communicating through a port 17 with the oil supply pipe which is threadedly engaged with the projection 18. A similar projection 19 threadedly positions a nut 21 having a valve 22, the purpose of which is to permit the priming when first starting up the engine. Secured to the lower end of the valve casting is a retaining nut 23 which holds the member 24 in engagement with the casting 5. This member 24 has a valve seat 26 against which the valve 27 rests. The valve 27 is carried upon the valve rod 13, the lower portion 27 being reduced in size and provided with oil channels 28 therein.

It will here be noted that the channel 16 communicates with an annular space 29 which in turn communicates through ports 31 with an annular space 32, the purpose of which will be later seen. Threadedly secured to the member 24 is the tip 33 having an opening 34 therein. This member 33 retains the atomizer disc 36 and the tip disc 37 in engagement with the member 24. A spreader cup 38 is attached to the tip 33 and has orifices 39 angularly disposed therethrough, the purpose of which will be later seen.

Referring now to Figure II, at 41 I have

shown a pipe through which an oil supply is adapted to pass and within this pipe is positioned an atomizer disc 36, a tip disc 37 which rest against a shoulder 42 formed adjacent the cup 38 having orifices 39 therethrough. The numbers given in this description of Figure II correspond to similar numbers in Figure I and refer to similar parts.

Referring now to Figure III it will be noted that the atomizer disc has a plurality of openings 43 passing therethrough which communicate with a recessed portion 44 centrally disposed in the disc through the medium of channels 46. These channels are formed tangentially to the outer circumference of the recess and are so arranged that the two channels on one side of the disc converge at substantially the same tangential point, while the two channels on the opposite side of the disc converge at this same tangential point. An upstanding cone 47 is formed in the recessed portion 44, the purpose of which will be later seen.

Referring now to Figure IV the tip disc 37 has an orifice 40 formed therein, a portion of which orifice is inclined as shown at 48.

The operation of my device is as follows:— First considering the use of the same in an internal combustion engine, and assuming that a heavy grade of oil such as Diesel oil is being used, the oil line will be connected to the projection 18 and by removing the screw 21 any air which is confined in the nozzle as a whole or in the line may be bled off after which the screw 21 is replaced. As soon as the pressure on the line is built up to a pre-determined amount which is controlled by the spring 11, the effect will be that the oil passing through the port 17 and channels 16 and into the annular recess 32 will push upwardly on the shoulder formed by the reducing portion of the valve rod and will raise the valve rod against the action of the spring 11. The oil will then flow through channel 28 past valve 27 and into the space immediately above the atomizing disc 36. The oil will then pass through the openings 43 thence through channels 46 and into the recess 44. This oil flowing through the channels 46 will result in giving the oil a whirling movement which will cause a vortex to be created about the cone 47. As there is only one path in which the oil can escape, namely through the orifice 34, the oil will pass therethrough in a whirling manner, and will pass out in a cone shaped spray as indicated by the dotted lines of Figure II. This will cause an injector effect which will suck in air as indicated in the arrows of Figure II, the air being furnished either from a natural draft as in the instance of a furnace or may be furnished through the usual air intake of the internal combustion engine, and being the air which in that in-

stance would be surrounding the valve tip projecting into the cylinder.

It has been found from actual tests that applicant's device will atomize heavy oils either for a continuous spray or for intermittent sprays, the atomization being so perfect that a single drop of oil will atomize and ignite, and due to the whirling action every particle of oil is sucked from the end of the device after the valve has closed and consequently there is no after drip.

It is to be understood that the form of my invention herewith shown and described is to be taken as a preferred example of the same and that various changes relative to the material, size, shape and arrangement of parts may be resorted to without departing from the spirit of the invention or the scope of the subjoined claim.

Having thus described my invention, I claim:—

A fuel atomizing nozzle having an oil supply, an atomizing disc positioned in said nozzle end having a recess formed therein, a plurality of channels extending tangentially with relation to said recess and formed in said disc, said channels being arranged in pairs and so that their point of contact with said recess converge at points on the opposite sides of said disc to cause rotation, a cone positioned in said recess, a tip disc superimposed on said atomizing disc, said tip disc having the orifice therethru, the tip of said cone being positioned in the plane between said two discs.

In testimony whereof I affix my signature.
PAUL LEO JOSLYN.
